E. A. SMITH

ROSIN DIPPER

Filed Aug. 18, 1926

UNITED STATES PATENT OFFICE.

EDWARD A. SMITH, OF VALDOSTA, GEORGIA.

ROSIN DIPPER.

Application filed August 18, 1926. Serial No. 130,094.

This invention relates to a dipper designed primarily for use in the dipping of rosin, but it is to be understood that a dipper, in accordance with this invention can be employed for any purposes for which it is found applicable, and the invention has for its object to provide, in a manner as hereinafter set forth a device of the class referred to including a dipper body, a handle secured therewith and disposed diametrically with the top thereof and means whereby the handle can be adjusted relatively to the dipper body for varying the dip with respect to the rosin container.

Further objects of the invention are to provide, in a manner as hereinafter set forth, a dipper for the purpose referred to which is simple in its construction and arrangement, strong, durable, compact, adjustable, thoroughly efficient in its use, conveniently handled, and inexpensive to manufacture.

With the foregoing and other objects in view, the invention consists of the novel construction, combination and arrangement of parts, as hereinafter more specifically described, and illustrated in the accompanying drawings wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a side elevation of a dipper in accordance with this invention.

Figure 2 is a vertical sectional view of the dipper and further illustrating the handle adjusted relative to the dipper body.

Figure 3 is a top plan view of the dipper.

Referring to the drawings in detail 1 denotes a dipper body, which is in the form of a bucket gradually increasing in diameter from its bottom to its top. The dipper body 1 is constructed of sheet metal of the desired gage and said dipper body at its top is formed with a peripheral reinforcing bead 2 which is coextensive with the circumference of said dipper body.

The dipper body 1 is formed with two sets of openings and said sets are diametrically opposed. The openings of each set are arranged in spaced relation and one of the opening of each set is positioned in proximity to the open top of the dipper body and

another opening of each of the sets is positioned in proximity to the closed bottom of the dipper body. The openings of one set are indicated at 3 and the openings of the other set are indicated at 4. The openings of the set 3 are the front openings and the openings 4 the rear openings. The bottom 5 of the dipper body 1 is upset as at 6 for reinforcing purposes.

Connected with the front of the dipper body 1 is a coupling member formed from a sheet metal strap of the desired gage and referred to generally by the reference character 7, and which includes a rigid inclined lower portion 8, a shiftable inclined upper portion 9 and an intermediate portion 10 which provides what may be termed a hinge connection between the portions 8 and 9 to provide for the adjusting of the portion 9 to various inclination with respect to the dipper body 1. The portion 9 extends across the open top of the dipper body 1. The portion 8 is of less height than the height of the dipper body 1 and is positioned against the front of the latter, as well as being secured therewith, by hold fast devices 11 which extend through the openings 3 and lower portion 8. The intermediate portion 10 extends from a point below the bead 4 at the front of the dipper body 1 and further extends over said bead 4 and inwardly with respect to the portion 8. The intermediate portion 10 is of curved contour.

Secured to the lower face of the portion 9 and of a length materially greater than the length of said portion 9 is a handle member 12 which projects rearwardly from the rear end or edge of the portion 9. Hold fast devices 13 are provided for fixedly securing the forward terminal part of the handle 12 to the portion 9. Removable hold fast devices 14 are provided for connecting the rear terminal part of the portion 9 to the handle member 12. The rear terminal part of the portion 9 is provided with a series of openings 15, arranged in spaced relation and which are adapted to selectively receive the hold fast devices 14. The handle member 12 is formed with a series of spaced openings 16 which register with the openings 15.

Associated with the dipper body 1 and handle member 12 is an adjusting element for said handle member and which further provides a support for the latter, as well as connects said handle member 12 with the

dipper body 1 at the rear thereof. The adjustable support is termed a heel and is formed from a metallic strap of the desired gauge and length and is indicated generally by the reference character 16. The heel is of angle shape and comprises an upstanding outwardly inclined leg 17 and a rearwardly directed and upwardly inclined leg 18 provided with openings 19 for the passage of the hold fast devices 14. The leg 16 is of materially greater length than the length of the leg 18 and said leg 17 is formed with a series of spaced openings 20 adapted to selectively align with the openings 4 and 15 extending through the alining openings are removable hold fast devices 21 for detachably securing the leg 17 to the dipper body 1 at the rear thereof.

By elevating or lowering the heel 16, the handle member will be supported in an elevated or a lowered position with respect to the dipper body and which provides for a varying dip with respect to the container for the rosin. The member 7 and heel 16, 25 or rather the portions thereof which are secured to the dipper body are diametrically opposed. The leg 18 of the heel 16 abuts against the lower face of the handle member 12 and is coupled therewith by the hold fast devices 14.

It is thought that the many advantages of a dipper, in accordance with this invention for the purpose referred to, can be readily understood, and although the preferred embodiment of the invention is as illustrated and described, yet it is to be understood that changes in the details of construction can be had which will fall within the scope of the invention as claimed.

40 What I claim is:

1. A dipper comprising an open top dipper body, a coupling member secured to the front thereof and including an inclined adjustable upper portion extending over the 45 open top of said dipper body, a handle secured to the inclined portion of said member and extending rearwardly from said

body, an upstanding support secured to the rear of said body and to said handle, said support being adjustable, and means for 50 fixedly securing the support to the dipper body to maintain the support in adjusted positions.

2. A dipper comprising a coupling member formed of a fixed lower portion and an 55 angularly adjustable upper portion, an open top dipper body arranged below said upper portion, means for fixedly securing said lower portion to said dipper portion, a handle secured to said upper portion, a vertically adjustable support, means for adjustably connecting said support to said dipper body, and means for adjustably connecting said support to said handle.

3. A dipper comprising a coupling member 65 formed of a fixed lower portion and an angularly adjustable upper portion, an open top dipper body arranged below said upper portion, means for fixedly securing said lower portion to said dipper portion, a handle secured to said upper portion, a vertically adjustable support, means for adjustably connecting said support to said dipper body, means for adjustably connecting said support to said handle, the means for adjustably 70 connecting the support to said handle further coupling said upper portion to the handle.

4. A dipper comprising a coupling member formed of a fixed lower portion and an 80 angularly adjustable upper portion, an open top dipper body arranged below said upper portion, means for fixedly securing said lower portion to said dipper portion, a handle secured to said upper portion, a vertically adjustable support, means for adjustably connecting said support to said dipper body, means for adjustably connecting said support to said handle, said support formed 85 of a pair of apertured legs angularly disposed with respect to each other.

In testimony whereof, I affix my signature hereto.

EDWARD A. SMITH.
